US00D968175S

(12) **United States Design Patent** (10) **Patent No.:** **US D968,175 S**
Barber (45) **Date of Patent:** **** Nov. 1, 2022**

(54) **CONTAINER**

(71) Applicant: **BRADSHAW HOME**, Rancho Cucamonga, CA (US)

(72) Inventor: **Tom Barber**, Manhattan Beach, CA (US)

(73) Assignee: **BRADSHAW HOME**, Rancho Cucamonga, CA (US)

(**) Term: **15 Years**

(21) Appl. No.: **29/739,193**

(22) Filed: **Jun. 23, 2020**

(51) LOC (13) Cl. **07-07**

(52) U.S. Cl.

USPC **D7/629**; D9/428; D9/425

(58) **Field of Classification Search**

USPC D9/414-426, 428-432, 500, 503, 504, D9/439, 452, 442, 502, 695, 696, 737, D9/739, 741, 742, 746, 747, 755, 756, D9/772, 774, 776-779, 425, 429; D7/601, 602, 538, 546, 547, 549, 400, D7/630, 540, 629

CPC B65D 2543/00148; B65D 43/021; B65D 1/30; B65D 1/22

(57) **CLAIM**

The ornamental design for a container, as shown and described.

DESCRIPTION

FIG. 1 is a top, front, right perspective view of the container showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a top, front, right perspective view, shown in an environment of use;

FIG. 9 is a top, front, right view thereof, shown in an environment of use; and,

FIG. 10 is a top plan view thereof, shown in an environment of use.

The broken line showing in the figures is for the purpose of illustrating portions of the container that form no part of the claimed design and, in FIGS. 8-10, the broken lines depicting a separate container represent environmental structure that forms no part of the claimed design.

1 Claim, 10 Drawing Sheets
